ESCUTCHEON FOR HARDWARE

Raymond U. H. Tegner, Lodi, Wis., assignor to
Amerock Corporation, Rockford, Ill.

Original design application Nov. 10, 1972, Ser. No.
305,567. Divided and this application Feb. 27,
1974, Ser. No. 446,118

Term of patent 14 years

Int. Cl. D8—09

U.S. Cl. D8—179

FIG. 1

FIG. 2

FIG. 3

FIG. 4

FIG. 5

FIG. 6

FIG. 7

FIG. 8

FIG. 10

FIG. 9

FIG.16

FIG.17

FIG.19

FIG.18

FIG.20

FIG. 1 is a side view of an escutcheon for hardware showing my new design as embodied in an escutcheon for a coat hook.

FIG. 2 is a front view of the escutcheon taken along the line 2-2 in FIG. 1.

FIG. 3 is a bottom view of the escutcheon.

FIG. 4 is a sectional view taken along the line 4-4 in FIG. 2.

FIG. 5 is a sectional view taken along the line 5-5 in FIG. 2.

FIG. 6 is a side view of an escutcheon for hardware showing my new design as embodied in an escutcheon for a door stop.

FIG. 7 is a front view of the escutcheon taken along the line 7-7 in FIG. 6.

FIG. 8 is a bottom view of the escutcheon shown in FIG. 7.

FIG. 9 is an enlarged sectional view taken along the line 9-9 in FIG. 7.

FIG. 10 is an enlarged sectional view taken along the line 10-10 in FIG. 7.

FIG. 11 is a side view of an escutcheon for hardware showing my new design as incorporated in an escutcheon for an entry handle.

FIG. 12 is a front view of the escutcheon taken along the line 12-12 in FIG. 11.

FIG. 13 is a bottom view of the escutcheon shown in FIG. 12.

FIG. 14 is a sectional view taken along the line 14-14 in FIG. 12.

FIG. 15 is a sectional view taken along the line 15-15 in FIG. 12.

FIG. 16 is a front view of an escutcheon for hardware showing my new design as embodied in an escutcheon for a deadlock.

FIG. 17 is a side view as seen from the right in FIG. 16.

FIG. 18 is a bottom view of the escutcheon shown in FIG. 16.

FIG. 19 is a sectional view taken along the line 19-19 in FIG. 16.

FIG. 20 is a sectional view taken along the line 20-20 in FIG. 16.

The portions shown in broken lines are for purposes of illustration and form no part of the design.

This application is a division of my co-pending application Ser. No. 305,567, filed Nov. 10, 1972.

I claim:

The ornamental design for an escutcheon for hardware, as shown and described.
